UNITED STATES PATENT OFFICE

102,051

DESIGN FOR A KNEELING RAIL OR SIMILAR ARTICLE

Leonard A. Goldsmith, Chicago, Ill.

Application August 31, 1936, Serial No. 64,644

Term of patent 14 years

To all whom it may concern:

Be it known that I, Leonard A. Goldsmith, a citizen of the United States and a resident of the city of Chicago, in the county of Cook and State of Illinois, have invented a new, original, and ornamental Design for a Kneeling Rail or Similar Article, of which the following is a specification, reference being had to the accompanying drawing, forming a part thereof.

On the drawing:

Figure 1 is a front elevational view of the kneeling rail showing my new design.

Figure 2 is a side elevational view thereof.

I claim:

The ornamental design for a kneeling rail, or a similar article as shown.

LEONARD A. GOLDSMITH.
